UNITED STATES PATENT OFFICE

HERBERT FISCHER AND LASAR GRODNITZKY, OF DARMSTADT, GERMANY

COOLING DEVICE

Application filed September 10, 1926, Serial No. 134,634, and in Germany, September 12, 1925.

Our invention relates to cooling devices, and more particularly to cooling plates which are used in the manufacture of soap, fat, tallow, chocolate, and the like. Heretofore, 5 said cooling plates have been made from cast or wrought iron, but we have discovered that various advantages may be obtained, if cooling plates are made of pressed parts, and therefore, the object of the present invention is to produce cooling plates which are made from pressed or stamped parts, either with or without the use of pressed or rolled corrugated sheet metal.

In the accompanying drawing, in which 15 we have shown, by way of illustration, various embodiments of our invention, Fig. 1 is a plan view of a complete cooling apparatus with the top plate removed; Fig. 2 is a longitudinal section along line 2—2 in Fig. 1, and 20 Fig. 3 is a transverse section along line 3—3 in Fig. 1; Fig. 4 shows a detail, partly in section, on a larger scale; Fig. 5 is another sectional detail view on a larger scale; Fig. 6 is a similar view as Fig. 1 showing a modification; Fig. 7 is a longitudinal section along line 7—7 in Fig. 6; Fig. 8 is a transverse section along line 8—8 in Fig. 6; Fig. 9 is an enlarged section through the frame of the device; Fig. 10 is a plan view of a modified 25 form of the frame; Fig. 11 is a section along line 11—11 of Fig. 10; Fig. 12 is an enlarged detail section on the line 12—12 of Fig. 10; Fig. 13 is a plan view of a modified cooling 30 device with a portion of the top plate broken away; Fig. 14 is a longitudinal section therethrough along line 14—14 in Fig. 13 and Fig. 35 15 is an enlarged detail view.

The cooling plate shown in Figs. 1—3 comprises two metal plates 1, 2, which are pressed 40 out or stamped in such a way as to form ribs 3 extending from the one edge of the plates and rising at or near the opposite edge, as clearly shown in Fig. 3, the ribs thus forming a series of troughs open at one end. The 45 two plates are so placed together that the ribs 3 of one plate alternate with those of the other, as clearly appears from Fig. 2, the open ends of the troughs formed by the ribs of one plate being on one side of the plates while the 50 open ends of the troughs formed by the ribs

of the other plate are on the opposite side. The ribs, besides imparting the required stiffness to the entire cooling device, also thus contribute to a favorable distribution of the cooling medium. The troughs formed by 55 the ribs 3 also receive blocks 4, placed at the open end of each trough, which blocks, as shown in Fig. 4, are held in place by screw-bolts 5 passing through the ribs. The blocks 4 may be welded or otherwise secured to the 60 cover-plates 6, 7 shown in Figs. 2, 3 and 4, which cover plates are thin plates preferably made of nickel, but which, of course, can be made of any other suitable material. Said cover plates are also preferably welded to the 65 plates 1, 2 which, for this purpose are chamfered, as shown at 8 in Figs. 1 and 2, to provide space for the welding seam.

The last rib 3 at or near one end of each plate 1, 2 is preferably made shorter than 70 the other ribs as clearly shown in Fig. 1, and in the remaining portion a channel 9 is provided for the passage of the material to be acted upon, said channel passing through the 75 cooling device without communicating with the interior thereof. This channel 9 which is shown more clearly in the sectional view of Fig. 5, may be made in the shape of a truncated cone, two flanged tubular and frusto-conical portions 10, 11 being pressed concentrically together in opposite relation to each other, and respectively attached to either of the two plates 1, 2.

In the modification of the cooling device shown in Figs. 6—8, the plates 12, 13 are provided with troughs formed by walls 14 which are pressed or stamped out from the metal of the plates 12, 13. These troughs also extend from one edge of each plate to near the opposite edge in alternating arrangement 90 thus constituting a tortuous passage for the cooling medium, while at the same time imparting stiffness to the plates 12, 13. The latter, at their ends are bent off as shown at 15 in Fig. 7 to form spaces for the welding 95 seams whereby the cover plates 16, 17 are secured to the plates 12, 13. This is more clearly shown in the enlarged view of Fig. 9.

Near the periphery of the plates 12, 13, there is provided a frame 18, which, as shown 100

in Figs. 10-12, may be made from pressed parts, such as channel shaped members 19 and suitable stiffening members 20. Said frame, as shown in Fig. 9 is likewise welded, 5 or otherwise secured, to the plates 12, 13 along the edges thereof.

As shown in Figs. 6 and 7, an inlet opening 21 is provided at or near the one end of the cooling device for the cooling medium to 10 enter the same, to pass beneath the cover plates in a sinuous path and to leave the device by an outlet opening 22 (Fig. 6) provided at or near the other end of the device. The ribs or walls of the cooling plates act as 15 baffles to divert the flow of the cooling medium.

The hollow portions of frame 18 may be left empty, or they may be filled with any suitable material to facilitate heat exchange, 20 and, of course, the frame may be constructed in any other way than shown in Figs. 10-12.

The device as above described, while equally adaptable both for heating and cooling is more especially designed for cooling soap, 25 fat, paraffin, chocolate, and the like as has been stated above.

A further modification of the device is disclosed in Figs. 13, 14 and 15. The cooling device as shown in said figures comprises two 30 plates 23, 24, which along their edges are connected by a frame 25. Between the two plates which are preferably made from nickel plated steel sheet metal, are pressed or rolled parts 26 which form trough shaped members 35 for the flow of the cooling medium and which are secured to the plates 23, 24. The channel for the passage of the material to be treated is shown at 27 in Fig. 13. At 28 is shown the inlet opening and at 29 the outlet opening 40 for the cooling medium.

The members 26 may be secured to the plates 23, 24 in any desired manner, but are preferably welded thereto, and the frame 25 is likewise preferably secured to the plates 45 23, 24 by welding.

Instead of the pressed or rolled member 26, also rolled or pressed corrugated sheet metal can be placed between the plates to form a passage for the cooling medium.

50 While we have shown and described various embodiments of our invention, we do not, of course, limit ourselves to the said embodiments as our invention is capable of various constructions.

55 What we claim is:—

1. In a heat exchange device, a pair of plates arranged in spaced overlying relation with respect to one another, means enclosing the space between said plates, ribs extending 60 from each plate into contact with the other plate, the ribs of each plate being disposed between and spaced from the ribs of the other plate, the ribs of one plate extending from one side of the device to points spaced inwardly from the other side of the device and 65

the ribs of the other plate extending from the latter side of the device to points spaced inwardly from the first mentioned side of the device, thereby to provide a single continuous tortuous passage extending from end to end 70 of the device.

2. In a heat exchange device, a pair of plates arranged in spaced overlying relation with respect to one another, means enclosing the space between said plates, ribs extending from each plate into contact with the other plate, said ribs being formed by integral inwardly directed portions of the respective plates, the ribs of each plate being disposed between and spaced from the ribs of the other plate, the ribs of one plate extending from one side of the device to points spaced inwardly from the other side of the device and the ribs of the other plate extending from the latter side of the device to points spaced inwardly from the first mentioned side of the device, thereby to provide a single continuous tortuous passage extending from end to end 75 of the device.

3. In a heat exchange device, a pair of plates arranged in spaced overlying relation with respect to one another, means enclosing the space between said plates, ribs extending from each plate into contact with the other plate, said ribs being formed by integral inwardly directed portions of the respective plates, the ribs of each plate being disposed between and spaced from the ribs of the other plate, the ribs of one plate extending from one side of the device to points spaced inwardly from the other side of the device and the ribs of the other plate extending from the latter side of the device to points spaced inwardly from the first mentioned side of the device, thereby to provide a single continuous tortuous passage extending from end to end 80 of the device.

4. In a heat exchange device, a pair of plates arranged in spaced overlying relation with respect to one another, means enclosing the space between said plates, hollow ribs of substantially U-shaped cross section pressed from each plate into contact with the other plate, the ribs of each plate being disposed between and spaced from the ribs of the other plate, the ribs of one plate extending from one side of the device to points spaced inwardly from the other side of the device and the ribs of the other plate extending from the latter side of the device to points spaced inwardly from the first mentioned side of the device, thereby to provide a single continuous tortuous passage extending from end to end 90 of the device, 100

5. In a heat exchange device, a pair of plates arranged in spaced overlying relation with respect to one another, means enclosing the space between said plates, hollow ribs of 105

substantially U-shaped cross section pressed from each plate into contact with the other plate, the ribs of each plate being disposed between and spaced from the ribs of the other plate, the ribs of one plate extending from one side of the device to points spaced inwardly from the other side of the device and the ribs of the other plate extending from the latter side of the device to points spaced inwardly from the first mentioned side of the device, thereby to provide a single continuous tortuous passage extending from end to end of the device, and cover plates secured against the outer faces of said first mentioned plates, respectively.

15 In testimony whereof we affix our signatures.

HERBERT FISCHER.
LASAR GRODNITZKY.
